APPARATUS FOR BURNING EXPLOSIVE GASEOUS MIXTURES.

1,113,171.

Specification of Letters Patent.

Patented Oct. 6, 1914.

Application filed January 8, 1913. Serial No. 410,220.

To all whom it may concern:

Be it known that I, FRANK CREELMAN, a citizen of the United States, residing at New York city, in the county of New York and State of New York, have invented certain new and useful Improvements in Apparatus for Burning Explosive Gaseous Mixtures, fully described and represented in the following specification and the accompanying drawings, forming a part of the same.

This invention relates to apparatus for burning explosive gaseous mixtures.

The invention has been made more particularly with the idea of improving apparatus of that class by which such mixtures are burned continuously or non-explosively as distinguished from non-continuous or intermittent combustion of such mixtures, and more especially to such apparatus in which back-flash or backward propagation of inflammation from the combustion chamber or space is prevented by causing the mixture to flow to the combustion chamber or space with a velocity greater than the rate of propagation of inflammation through the mixture, and in which the surface or zone of combustion is then localized and blow-off prevented by rapidly reducing the flow velocity of the mixture. Various styles of apparatus have been made which operate successfully in this way. More or less difficulty has, however, been encountered in maintaining the continuous and localized combustion of explosive gaseous mixture for long periods of time with apparatus that is otherwise wholly effective, resulting from the conduction of heat backward from the zone where it is generated through solid matter constituting the walls of the supply passages and consequent ignition of the mixture at a place where it may be moving with a velocity less than the rate of propagation of inflammation. This difficulty is not met with so much, being more easily obviated by the natural design of the apparatus in burners or apparatus where the mixture is supplied through a single supply orifice or passage or a comparatively small number of supply orifices or passages, but becomes more serious when it is desired to supply the mixture through a larger number of supply passages arranged to distribute the mixture in the combustion chamber or space. With such an apparatus, it is desirable that

the comparatively small supply passages 55 through which the mixture is caused to flow to the combustion chamber or space shall be as short as possible consistent with the attainment of the necessary cooling action in order to avoid excessive friction losses which necessitate increased power to compress and feed the mixture, and in order, also, to permit of a more compact and simple structure than would otherwise be possible. It is desirable, therefore, in a burner or apparatus 65 of this kind that the mixture may be fed at a comparatively low velocity to a fairly large supply chamber adjacent to the combustion space or chamber and from which the mixture is supplied to the combustion 70 chamber through a plurality of comparatively small supply passages of such size and so spaced with respect to each other at their delivery ends as to supply and properly distribute the proper amount of mixture to generate the desired total heat per square foot of final heating surface. The closer the supply chamber is to the combustion space, however, and the shorter the supply passages, the greater the liability of ignition of 80 the mixture in the supply chamber by heat conducted back through the structure.

The present invention aims to provide an apparatus fulfilling these requirements and whereby the conduction of heat from the 85 combustion zone backward to the supply chamber to such an extent as might cause ignition of the mixture in the supply chamber is prevented, and which shall yet be of comparatively simple and inexpensive construction and of high efficiency.

An understanding of the invention can best be given by a description of a preferred form of apparatus embodying the various features of the invention, and such a description will now be given in connection with the accompanying drawings showing such a preferred apparatus, and in which:

Figure 1 is a sectional view of the burner. Fig. 2 is a plan view of the face of the burner 100 with the pieces of refractory material forming the combustion bed shown in Fig. 1 removed; Fig. 3 is a general view on a reduced scale showing the burner with means for supplying the gaseous mixture thereto. Fig. 105 4 is a plan view and Fig. 5 is a sectional view of a cover for the burner.

Referring to the drawings, the burner A

comprises a body portion 10, a combustion supporting bed 11 supported against one face of the body 10, and a supply chamber 12 adjoining another face of the body 10, the body being formed with a plurality of small supply passages 13 extending from the supply chamber to deliver the gaseous mixture to the combustion bed. The portion of the body adjacent the combustion bed should be 5 of a suitable material sufficiently refractory to withstand the great heat to which it is subjected and preferably of low heat conductivity, a suitable cement such as alundum cement being preferably used; and in the 10 preferred construction shown the body is for simplicity and for convenience in manufacture made of a single molded mass of plastic material extending from the part adjacent to the combustion bed to the supply chamber 15 20 25 30 35 40 45 50 55 60 65 70 75 80 85 90 95 100 105 110 115 120 125 130

12, and preferably inclosed within a cast or other suitable metal casing 15, which casing may be extended to form the walls of the supply chamber 12 as shown. The plastic material may be molded in the casing and may be wholly of alundum cement or other highly refractory material, or the lower part of the body filling, or part farthest away from the combustion space, where the temperature is not so high may be made of a material which, though not so highly refractory as the material forming the upper part, is of lower heat conductivity. For example, in the burner shown in the drawings the refractory material above the dotted line α might be alundum cement or other suitable highly refractory material and the part below such dotted line of a material, such as magnesium carbonate, kaolin or asbestos stove lining cement, which is not so highly refractory as the alundum cement but is a better non-conductor of heat. The supply chamber is provided with a suitable clean-out opening normally closed by a screw plug 16, and is supplied with the explosive gaseous mixture through an inlet pipe 17 leading from any suitable source of supply.

The combustion bed 11 in the preferred form of burner illustrated is made up of a mass of broken or other suitable pieces of highly refractory material such as alundum, chrome ore or magnesite, or even fire-brick where a gas of low heating power is to be burned. The pieces or granules of refractory material forming the bed may be bonded together in any suitable manner or a bed of loose unbonded pieces or granules may be used. When the bed is formed of loose pieces of refractory material, suitable means will be provided for retaining the same in position. The body is conveniently formed with a recess in its face to receive and hold in place the pieces of refractory material forming the bed, and when the burner is to be used in an upright position as shown 65 with the bed supported in a horizontal posi-

tion or in the upper face of the body 10, no additional means will ordinarily be needed to hold the material of the bed in place. The bed may be of any superficial size and of various thicknesses, and the size of the pieces or granules of refractory material composing the bed will vary according to the size of the bed and especially its depth or thickness.

The particular form of burner illustrated is intended primarily for use as a cook stove burner, and with such a burner it is especially desirable that the temperature of the bed may be raised to the desired maximum intensity in a minimum length of time. It is desirable, therefore, that the bed shall be comparatively thin or shallow, and in order that a suitable distribution of the mixture supplied to such bed may be obtained it becomes desirable that the supply passages shall be in greater number than would be required to secure the proper distribution for a bed of greater thickness, each passage being of comparatively smaller size than it would be desirable to use with a bed of greater thickness and the mixture being sometimes supplied with a velocity not so greatly in excess of the rate of propagation of inflammation as would usually be employed with a thicker bed. With such a construction, therefore, the prevention of heat conduction from the combustion bed back through the structure to a point where the mixture is not moving with a velocity in excess of the rate of propagation of inflammation becomes more difficult.

In the use of the burner shown, when the gaseous mixture is supplied to the chamber 12 and maintained under such pressure in the chamber that the mixture flows through the supply passages with a velocity in excess of the rate of propagation of inflammation of the mixture, as the mixture passes from the supply passages into the porous and permeable combustion bed, it is caused to spread out and advance in increasing volume and with rapidly decreasing velocity, so that its velocity is reduced to the rate of propagation of inflammation within the limits of the bed. The mixture having been ignited, the surface or zone of combustion will then locate within or at the surface of the bed at the zone or surface where equality between the flow velocity and the rate of propagation of inflammation is attained. The combustion being extremely intense, the pieces of refractory material forming the combustion bed will be quickly raised to, and thereafter maintained at, a very high temperature, so that the bed becomes highly incandescent and the heat generated by the combustion becomes available not only by conduction through the escaping products of combustion the temperature of which will be very high, but also to a very large degree

as radiant heat from the glowing refractory bed.

It will be observed that the space occupied by the combustion bed is the space or chamber in which the combustion takes place, and that the function of the bed is mainly two-fold, namely; to distribute and rapidly reduce the flow velocity of the gaseous mixture within the combustion space or chamber by causing the mixture to spread out as it advances, and secondly, to serve as a source of radiant heat after it becomes heated by the combustion taking place within it or at its outer surface. Other forms of porous and permeable combustion beds might, of course, be employed, and various other means provided for quickly reducing the flow velocity of the mixture as it leaves the high velocity supply passages.

In order to avoid the heating of parts of the structure adjacent to the supply chamber 12 by conduction of heat from the combustion zone to a temperature which might cause ignition of the mixture within the chamber 12, the body of the burner is so made that there shall be a path for the flow of heat from any point of the body adjoining the combustion bed to a part of the body from which the heat may radiate or otherwise escape, which path shall be of less resistance to heat flow than the path which the heat would have to traverse from such point adjoining the combustion bed to reach a part of the body or burner structure adjoining the chamber 12. To secure this result to an efficient degree and without unduly increasing the length of the burner body in the direction from the combustion bed to the chamber 12, I arrange the supply passages 13 so that they shall be grouped more closely together at their inlet or supply chamber ends than at their outlet or combustion chamber ends, which latter ends are necessarily spread apart to the extent necessary for properly distributing the mixture supplied to the combustion chamber or space, the supply passages being preferably straight passages arranged to spread out or radiate in the direction from the supply chamber to the combustion chamber, and I form the body with sides slanting outwardly in the direction from the supply chamber toward the combustion chamber, and preferably with an enlarged outer or upper end or head portion to accommodate the depression forming the combustion chamber and in which the bed of refractory material in the construction shown is located. The slanting sides *a* of the body 10 preferably conform substantially to the direction of the outermost passages 13, and such passages extend closely adjacent to said side surfaces. With the body so shaped in cross-section and proportioned substantially as shown in Fig. 1, the distance through which heat from the

combustion bed must pass from any point of the combustion bed to reach the surface of the body is considerably less than the distance through which the heat must travel from such point of the combustion bed to reach a part of the burner structure adjoining the supply chamber 12. Therefore, with the surface of the body 10, and especially the surface of the outwardly inclined sides *a* of the body, free to act as radiating or heat discharging surfaces, the abstraction of heat from the body by discharge from said surfaces will effectually prevent the raising of any part of the structure adjoining the supply chamber to a temperature which might cause ignition of the gaseous mixture in said chamber. It is found that prevention of ignition of the mixture in the supply chamber will thus be secured through long periods of operation of the burner when the medium in contact with the sides *a* of the body 10 for receiving heat therefrom is merely moving atmospheric air, but obviously, suitable arrangements might be provided whereby other cooling media might be supplied for receiving heat from the walls *a*. It is, however, of course desirable especially in small burners, to avoid the necessity of complicating the structure and especially of providing power driven means for circulating water or other cooling fluids. The body of the burner might, obviously, be otherwise shaped to provide such shorter path and resulting lower resistance to a radiating or discharging surface at a point removed from the supply chamber 12, but a body having the supply passages therein arranged to spread out or radiate in the direction of the flow of the mixture therethrough, as from a common point or line, and with its lower portion of largely reduced size as compared with the part adjacent the combustion space and having its sides formed to slant outwardly in the direction away from the supply chamber makes it practicable to make a burner having a solid, and even homogeneous, body through which the supply passages extend and whose dimension in the direction from the supply chamber to the combustion chamber is comparatively small, the supply chamber being located comparatively close to the combustion chamber and the whole structure being of very compact as well as simple and inexpensive construction.

With the burner constructed as shown and having a homogeneous filling within the casting, the relative resistance to the flow of heat from the combustion chamber to the heat discharging walls of the burner and to the supply chamber depends upon the distance of the heat discharging walls and supply chamber respectively from the combustion chamber; but it is obviously not necessary that the relative resistance of

such paths of flow of heat should depend solely upon or even at all upon the relative lengths of such paths.

Making the lower portion of the body, or 5 the portion farthest away from the combustion zone, of material which is a better non-conductor of heat than the highly refractory material nearer the combustion zone, as hereinbefore described, has the advantage of 10 affording some additional protection against the conduction of heat to the supply chamber because of the insulating property of the material forming the lower part of the body and also to some extent probably be- 15 cause of the greater relative resistance offered to flow of heat toward the supply chamber resulting from the transverse stratification of the body. It should be observed, however, that my burner structure does not 20 depend upon the use of non-heat-conducting material to prevent the transmission of heat through the structure to the supply chamber, or place where the mixture is moving with a velocity less than the rate of propagation 25 of inflammation of the mixture. It is desirable, however, to make use of highly refractory material because of the extremely high temperature to which it is subjected, and it is also of advantage that such ma- 30 terial be of low heat conductivity principally in order to lessen the loss of heat by conduction through the burner body.

The mixture may be supplied to the supply chamber 12 from any suitable source or 35 means of supply. As shown, a mixture of a suitable fuel gas and air is supplied by means of a fan 20 delivering into the pipe 17, the fan drawing the gas through a pipe 21 leading from any suitable source and 40 air through an inlet pipe 22. The gas supply pipe 21 and air inlet pipe 22 are provided with suitable controlling valves 23 and 24 respectively by which the proportionate amounts of gas and air drawn into the 45 fan to be supplied to the burner may be controlled. These valves thus serve to control the relative proportions of gas and air in the mixture, and might be used to control the total amount of mixture supplied 50 to the burner. The amount of mixture is better controlled, however, by controlling the speed of the fan or by a valve in the supply pipe 17 as shown at 25. The proper proportions of fuel gas and air, or combustion supporting gas, that is, proportions such according to the nature of the constituent gases that the gaseous mixture supplied to the burner shall have the property of self-propagation of inflammation, and 55 the proper amount of mixture to be supplied to maintain the necessary or desired pressure in the chamber 12 of the burner, may be readily determined by experiment. The highest temperature will of course be 60 generated by a mixture in which the fuel

gas and oxygen of the air are substantially in chemical combining proportions. With such a mixture the products of combustion leaving the combustion bed will be neutral. It should be noted, however, that by sup- 70 plying a mixture having an excess of oxygen oxidizing products of combustion may be obtained; and by supplying the mixture with an excess of fuel gas reducing products may be obtained, the fuel gas which is 75 not consumed within the combustion bed then burning beyond the bed with the aid of oxygen subsequently supplied thereto from the atmosphere or otherwise. In all cases, however, the excess of any constituent 80 of the mixture must not be sufficient to make the mixture non-explosive.

In order to avoid interference with the flow of gaseous mixture from the supply passages by pieces or granules of a combustion bed such as shown, the face of the burner body adjacent which the combustion bed rests is formed with grooves 85 extending from the ends of the passages, as shown, for example, in Figs. 1 and 2. These grooves 90 provide for free escape of the gaseous mixture from each passage even though a piece or granule of the combustion bed might be located directly against the outlet end of the passage so that except for the grooves 95 the flow of mixture from the passage would be more or less blocked.

As before stated, the particular burner illustrated in the drawings is intended primarily to be used as a cook stove burner 100 or for other similar purpose for which it may be found suitable, and as being most convenient for this purpose the burner is made round in cross-section so as to provide a round topped burner. Obviously, 105 however, the burner might be made to provide a head portion, or part adjacent to which the combustion takes place, of other suitable desired shape and the structure might then be of corresponding shape in 110 cross-section.

Even when the burner is to be used with the combustion bed in a horizontal position, whether as a cook stove or for other purpose, it may sometimes be desirable to provide a cover to extend over the combustion bed. In Figs. 3, 4 and 5 I have shown a flat cover 30 intended especially for a cook stove burner. The cover 30 is of perforated or skeleton construction to permit the passage of the products of combustion and radiant heat, and to avoid warping and cracking is made up of a plurality of concentric bands or rings 31 formed to seat one within another. As shown, the cover is 115 round to fit over a round topped burner and the sections 31 are of annular form, but the shape of the cover will obviously be varied to suit the shape of the burner. Each section may be removed independently of 120 125 130 135

- the next outer adjoining section so that more or less of the combustion bed may be uncovered as desired. The upper face of the cover is formed with separated projections or lugs 5 32 by which a vessel set on the cover is supported above the main body of the cover so as to leave space for the passage of the products of combustion from the explosive fire. As shown, these projections excepting 10 the outermost ones are the lugs by which each inner section of the cover is supported on the next outer one. The cover may be made of any suitable refractory material. A sectional cover of the form shown made 15 of iron gives good service on a cook stove burner under ordinary use. Where higher temperatures are produced, the cover should be made of a more highly refractory material.
- 15 It will be understood that the invention is not to be limited to the exact construction, arrangement and form of the burner and apparatus shown and to which the foregoing description has been largely confined, 20 but that it includes changes and modifications thereon within the claims.
- What is claimed is:
1. An apparatus for burning explosive gaseous mixtures comprising in combination 25 a structure providing a combustion chamber, a mixture supply chamber adjacent to the combustion chamber, and a body between said chambers having a plurality of supply passages therein for the flow of the 30 explosive mixture from the supply chamber to the combustion chamber, means for maintaining a supply of the explosive mixture in the supply chamber under pressure sufficient to cause the mixture to flow through the 35 supply passages with a velocity greater than the rate of propagation of inflammation through the mixture, and means within the combustion chamber for reducing the flow velocity of the mixture, said body having a 40 heat discharging surface and being formed to provide a path of less resistance to the flow of heat from any point adjoining the combustion chamber to a heat discharging surface thereof than the path through said body from such point to the supply 45 chamber.
  2. An apparatus for burning explosive gaseous mixtures comprising in combination 50 a structure providing a combustion chamber, a mixture supply chamber adjacent to the combustion chamber, and a body between said chambers having a plurality of supply passages therein for the flow of the 55 explosive mixture from the supply chamber to the combustion chamber, means for maintaining a supply of the explosive mixture in the supply chamber under pressure sufficient to cause the mixture to flow through the supply 60 passages with a velocity greater than the rate of propagation of inflammation through the mixture, and means within the combustion chamber for reducing the flow velocity of the mixture.
5. An apparatus for burning explosive gaseous mixtures comprising in combination 65 a structure providing a combustion chamber, a mixture supply chamber adjacent to the combustion chamber, and a body between said chambers having a heat discharging surface and being shaped to provide a path of less length for the flow of heat from any point adjoining the combustion chamber to a heat discharging surface thereof than the path through said body from such point to the supply chamber.
3. An apparatus for burning explosive gaseous mixtures comprising in combination 70 a structure providing a combustion chamber, a mixture supply chamber adjacent to the combustion chamber, and a body between said chambers having a heat discharging surface and shaped with the portion thereof near the combustion chamber of greater cross sectional size than the portion thereof near the supply chamber to provide a path of less resistance to the flow of heat from any point adjoining the combustion chamber to a heat discharging surface of said body than the path through said body from such point to the supply 75 chamber, and said body having a plurality of mixture supply passages therein leading from the supply chamber to the combustion chamber, means for maintaining a supply of the explosive mixture in the supply chamber under pressure sufficient to cause the mixture to flow through the supply passages with a velocity greater than the rate of propagation of inflammation through the mixture, and means within the combustion 80 chamber for reducing the flow velocity of the mixture.
4. An apparatus for burning explosive gaseous mixtures comprising in combination 85 a structure providing a combustion chamber, a mixture supply chamber adjacent to the combustion chamber, and a body between said chambers shaped with heat discharging sides slanting outwardly in the direction from the supply chamber to the combustion chamber to provide a path of less resistance to the flow of heat from any point adjoining the combustion chamber to a heat discharging surface of said body than the path through said body from such point to the supply chamber, and said body having a plurality of mixture supply passages therein leading from the supply chamber to the combustion chamber, said passages being spaced apart a greater distance at their delivery ends than they are adjacent to the supply chamber, means for maintaining a supply of the explosive mixture in the supply chamber under pressure sufficient to cause the mixture to flow through the supply passages with a velocity greater than the rate of propagation of inflammation through the mixture, and means within the combustion chamber for reducing the flow velocity of the mixture.

5. An apparatus for burning explosive gaseous mixtures comprising in combination a structure providing a combustion chamber, a mixture supply chamber adjacent the combustion chamber, and a body between said chambers shaped with heat discharging sides slanting outwardly in the direction from the supply chamber to the combustion chamber to provide a path of less resistance 10 to the flow of heat from any point adjoining the combustion chamber to a heat discharging surface of said body than the path through said body from such point to the supply chamber, and said body having a plurality of straight mixture supply passages 15 therein leading from the supply chamber to the combustion chamber and spreading apart in the direction from the supply chamber to the combustion chamber, means 20 for maintaining a supply of the explosive mixture in the supply chamber under pressure sufficient to cause the mixture to flow through the supply passages with a velocity greater than the rate of propagation of inflammation through the mixture, and means 25 within the combustion chamber for reducing the flow velocity of the mixture.
6. An apparatus for burning explosive gaseous mixtures comprising in combination 30 a structure providing a combustion chamber, a mixture supply chamber adjacent the combustion chamber, and a body between said chambers having a plurality of mixture supply passages leading from the supply chamber to the combustion chamber, said 35 passages spreading apart in the direction from the supply chamber to the combustion chamber, and said body being shaped with outwardly slanting heat discharging sides 40 walls conforming substantially to the outer passages to provide a path of less resistance to the flow of heat from any point adjoining the combustion chamber to a heat discharging surface of said body than the path 45 through said body from such point to the supply chamber, means for maintaining a supply of the explosive mixture in the supply chamber under pressure sufficient to cause the mixture to flow through the supply 50 passages with a velocity greater than the rate of propagation of inflammation through the mixture, and means within the combustion chamber for reducing the flow velocity of the mixture.
7. An apparatus for burning explosive gaseous mixtures comprising in combination a structure providing a mixture supply chamber and a body having a plurality of supply passages for the flow of the explosive mixture from the supply chamber, said 55 passages opening through a face of the body removed from the supply chamber, means for maintaining a supply of the explosive mixture in the supply chamber under pressure sufficient to cause the mixture to flow 60 through the supply passages with a velocity greater than the rate of propagation of inflammation through the mixture, and means within the combustion chamber for reducing the flow velocity of the mixture.
8. A burner for burning explosive gaseous mixtures embodying therein a structure providing a combustion chamber, a mixture supply chamber adjacent the combustion chamber, and a body between said chambers circular in cross-section and shaped with heat discharging walls which slant outwardly in the direction from the supply chamber to the combustion chamber to provide a path of less resistance to the flow of heat from any point adjoining the combustion chamber to a heat discharging surface 70 of said body than the path through said body from such point to the supply chamber.
9. A burner for burning explosive gaseous mixtures embodying therein a porous and permeable combustion bed of loose pieces 75 of refractory material, and a structure providing a mixture supply chamber adjacent the combustion bed and a body between the combustion bed and the supply chamber and against which the combustion bed is supported, said body having a heat discharging wall and having a plurality of mixture supply 80 passages therein leading from the supply chamber to the combustion bed and spaced apart a greater distance at their delivery ends than at their supply chamber ends, and said body being formed to provide a path of less resistance to the flow of heat from any point adjoining the combustion bed to a heat discharging surface thereof than the path through said body from such point to the supply chamber.
10. A burner for burning explosive gaseous mixtures embodying therein a body having a face formed with a recess to receive a porous and permeable combustion bed of loose pieces of refractory material, a mixture supply chamber adjoining the body, the body having a plurality of supply passages 110 therein for the flow of the explosive mixture.

from the supply chamber to said recess and being shaped to provide a path of less length for the flow of heat from any point adjoining said recess to a heat discharging face of the body than the path through said body from such point to the supply chamber.

11. A burner for burning explosive gaseous mixtures embodying therein a mixture supply chamber, a body having an enlarged head portion and a portion of reduced cross sectional size between the head portion of the body and the supply chamber and having heat discharging sides slanting outwardly in the direction from the supply chamber to the head portion of the body, and having a plurality of mixture supply passages therein leading from the supply chamber to the outer surface of the head portion of the body adjacent to which the combustion takes place, and means for reducing the flow velocity of the explosive mixture issuing from said supply passages.

12. A burner for burning explosive gaseous mixtures embodying therein a body formed of a metal casing and a filling of refractory material within the metal casing and having an exposed face, a porous and permeable combustion bed supported against the exposed face of said filling of refractory material, and a mixture supply chamber adjoining said body, said body having a plurality of mixture supply passages leading from the supply chamber through said filling to the combustion bed, and said body having a heat discharging surface and being formed to provide a path of less resistance to the flow of heat from any point adjoining the combustion bed to a heat discharging surface of the body than the path through said body from such point to the supply chamber.

13. A burner for burning explosive gaseous mixtures embodying therein a body formed of a metal casing and a filling of refractory material within the metal casing and having an exposed face, a porous and permeable combustion bed supported against the exposed face of said filling of refractory material, and a mixture supply chamber adjoining said body, said body having a plurality of mixture supply passages leading from the supply chamber through said filling to the combustion bed, and said body having a heat discharging surface and being formed to provide a path of less length for the flow of heat from any point adjoining the combustion bed to a heat discharging surface of the body than the path through said body from such point to the supply chamber, and said filling being formed of two kinds of refractory material, the portion nearest the combustion bed being the more highly refractory and a portion nearer the supply chamber being of lower heat conductivity.

14. A burner for burning explosive gaseous mixtures embodying therein a body of refractory material, and a mixture supply chamber adjoining the body, the body having a heat discharging surface and having a plurality of mixture supply passages therein leading from the supply chamber to a surface of the body adjacent to which the combustion takes place and being formed to provide a path of less length from any point in the face thereof adjacent to which the combustion takes place to a heat discharging surface of the body than the path through said body from such point to the supply chamber, and said body being formed of two kinds of refractory material, the portion nearest the surface adjacent to which the combustion takes place being the more highly refractory and a portion nearer the supply chamber being of lower heat conductivity.

15. A burner for burning explosive gaseous mixtures embodying therein a casting forming the casing of a supply chamber and the shell or casing of the body portion of the burner, a molded filling of refractory material within the body casing portion of the casting and having an exposed face, and a porous and permeable combustion bed supported against the exposed face of said filling, said filling having a plurality of mixture supply passages extending therethrough from the supply chamber to the combustion bed, and the body casing portion of the casting having a heat discharging surface and being shaped to provide a path of less length for the flow of heat from any point adjoining the combustion bed through the filling and to a heat discharging surface of the casting than the path through said filling from such point to the supply chamber.

16. A burner for burning explosive gaseous mixtures embodying therein a porous and permeable combustion bed of loose pieces of refractory material, and a body against which the combustion bed is supported having a plurality of mixture supply passages therein leading to the face thereof adjoining the combustion bed, the face of the body being provided with grooves leading from the discharge ends of said supply passages, whereby blocking of the flow of the mixture from the passages by pieces of the combustion bed is avoided.

17. A burner for burning explosive gaseous mixtures embodying therein a porous and permeable combustion bed, and means providing a mixture supply passage leading to the combustion bed, said passage being enlarged at its outlet end to avoid blocking of the flow of the mixture from the passage by solid portions of the combustion bed.

18. An apparatus for burning explosive gaseous mixtures comprising in combination

a flat horizontally disposed porous and permeable combustion bed, a burner body by which the combustion bed is supported and which is formed with a plurality of supply 5 passages for supplying the gaseous mixture to the combustion bed, means for supplying the explosive mixture to said passages under pressure sufficient to cause the mixture to move through the passages with a velocity greater than the rate of propagation

of inflammation through the mixture, and a perforated cover resting on the burner body.

In testimony whereof I have hereunto set my hand in the presence of two subscribing 15 witnesses.

FRANK CREELMAN.
